UNITED STATES PATENT OFFICE

ROBERT ERN, OF SOLINGEN, GERMANY

POLISHING APPARATUS, SPECIALLY FOR KNIVES, FORKS, AND SPOONS

Application filed May 29, 1930, Serial No. 457,457, and in Germany June 3, 1929.

This invention relates to a polishing apparatus specially for knives, forks and spoons, composed of a rotating polishing wheel and a disc arranged at the side of the polishing wheel rotating comparatively slowly, similar to a turret head and carrying the articles and bringing the same against the polishing wheel.

According to the invention oscillatable levers are mounted on the feeding disc so that they project beyond the disc rim, said levers carrying on their extreme ends the knives, forks and spoons and being held by suitable means, for instance springs and eventually by stops in a certain position with regard to the polishing wheel so that, during the polishing, they are pressed together with the knives, forks and spoons at varying adjusting angles against the polishing wheel.

In comparison with the polishing apparatus of known type in which the adjusting angle between the grinding tools and the carrier of the knives, forks and spoons is always the same, so that a uniform polishing of all the articles is not possible, the important advantage is attained by the invention that the articles to be polished are worked upon by the polishing disc at changing angles of presentation similar as in the case of manual treatment. A completely mechanical polishing work is therefore obtained and of the same quality as when the work is done by hand. The apparatus presents further the advantage of great simplicity and serviceability.

In order that the articles when passing along the polishing wheel may be treated not only in one direction, but in different directions, the levers employed, which project over the rim of the carrying or feeding disc and oscillatable in their plane, are also controlled by yieldable elements.

Several embodiments are illustrated by way of example in the accompanying drawings in which

Fig. 1 shows the polishing apparatus in side elevation.

Fig. 2 shows also in side elevation a second form of construction of the polishing apparatus.

Fig. 3 is a top plan view of Fig. 2.

Figs. 4 and 5 illustrate in two different positions the levers carrying the articles.

Referring to Fig. 1 a disc 3 is rotatably mounted on a shaft 2 journalled in a frame 1, said disc carrying studs 4 on its circumference, on which two-armed levers 5 are oscillatably mounted. Suitable means 7 for holding the articles to be polished, for instance spoons 8, are arranged on the outer ends 6 of the double armed levers. Spiral springs 10 are attached on the inner ends of the double armed levers 5 and fixed at their other end to pins 11. These springs can pull the double armed levers 5 against stops 12. At the side of the frame 1 carrying the disc 3 a frame 13 with a polishing wheel 14 is arranged, this wheel being constructed as a polishing cloth wheel.

The disc 3 for carrying the articles to be polished as also the polishing wheel 14 are rotated in the same direction indicated by arrows, the polishing wheel 14, rotating preferably at high speed in order to obtain a good polishing effect. The wheel 3 has a comparatively large diameter and rotates, compared with polishing wheel 14, at a slow speed in order that the articles to be polished may be carried through the polishing wheel for the period necessary to obtain a good polishing effect. The slow revolving speed of wheel 3 is practical in order that the person attending the apparatus can place during the rotation of wheel 3 the articles to be polished onto the double armed levers 5 and remove the polished articles from these levers.

It is clear that the double armed levers 5 are oscillated around their pivot bolts 4 and move away from the abutment pins 12 as soon as they or the articles to be polished arrive on the path of the polishing wheel. According to the kind of resistance offered by the polishing wheel the springs 10 have the tendency to return the double armed levers 5 into their initial position. In this manner the articles to be polished are not only subjected to a circulating movement produced by the wheel 3 but submitted also to an oscillating movement around the bolts 4. The double movement obtained in this manner

permits of adapting the polishing work to the shape of the article to be polished and assists considerably in perfectly attaining the desired polishing effect.

5 According to Fig. 2 levers 16, oscillatable around pivot pins 15 and controlled by springs 10, are mounted on the levers 5 oscillatably mounted on pivot pins 4 of wheel 3. The articles 8 to be polished being attached to 10 said levers 16 are also controlled by springs, the arrangement being such that when the polishing wheel 14 is not acting upon the articles these levers 16 are parallel to the axle 2.

15 The polishing wheel carries out, as can be seen from Fig. 4, first a polishing in transverse direction. The lever 16 is, as shown in Fig. 5, gradually oscillated at the continuing rotation of disc 3. It assumes by and by the 20 position of the lever 6 and returns from this position gradually into the initial position shown in Fig. 4.

It is evident that the transverse polishing is gradually transformed into longitudinal polishing, the adjustable angle of presentation of the articles to be polished being at the 25 same time displaced in the plane of the wheel through the action of the springs 10.

Experiments have shown that by this apparatus the polishing of articles can be finished without preliminary treatment, this being specially important for such articles which are difficult to polish owing to their shape or material.

I claim:

- 35 1. An apparatus for polishing articles, such as knives, forks, spoons or the like, comprising in combination a rotating flexible laminated polishing wheel, a turret like article carrying disc disposed adjacent said 40 wheel and adapted to rotate at a slower speed than said wheel and to present said articles to said wheel, oscillatable levers pivoted to said disc and adapted to project beyond the rim thereof, article carrying members pivoted to said levers for movement in planes perpendicular to the plane of said disc, spring 45 means connecting said disc with said levers and adapted to urge said levers toward their initial extended positions, stops on said disc 50 for holding said levers in said extended positions, resilient means for urging said article carrying members toward positions transverse to the plane of said disc, said disc and said wheel being so closely disposed with relation to each other that said articles are adapted 55 to be embedded to some extent within the surface of said wheel, whereby the frictional contact will cause said levers and said members to yield so as to present said articles to 60 said wheel at varying angles both within the plane of said disc and perpendicularly thereto, thus effecting the gradual transformation of transverse polishing to longitudinal polishing.

65 2. An apparatus for polishing articles,

such as knives, forks, spoons or the like, comprising in combination a rotating flexible polishing wheel, a turret like article carrying member supported adjacent said wheel for rotation at a slower speed than said wheel 70 to present said articles successively to said wheel, a plurality of elements pivoted to said member for oscillation about axes substantially parallel to the axis of rotation of said member, an article carrying element pivoted to each of said oscillatable elements for movement under the influence of contact with said wheel in planes perpendicular to the plane of rotation of said member, and yielding means 75 acting between said member and said first named elements for urging the latter about their pivotal points into contact with the said wheel, said member and wheel being so closely disposed with relation to each other that contact of the articles with said wheel 80 will cause said first mentioned elements to yield and present said articles to said disc at varying angles in a plane substantially perpendicular to the axis of rotation of said member.

In testimony whereof I affix my signature.
